UNITED STATES PATENT OFFICE.

WILLIAM A. LORENZ, OF HARTFORD, CONNECTICUT, ASSIGNOR OF TWO-THIRDS TO WILLIAM H. HONISS, OF SAME PLACE, AND HERMAN BEHR, OF BROOKLYN, NEW YORK.

TOILET-PAPER.

SPECIFICATION forming part of Letters Patent No. 550,280, dated November 26, 1895.

Application filed October 10, 1894. Serial No. 525,479. (No model.)

To all whom it may concern:

Be it known that I, WILLIAM A. LORENZ, a citizen of the United States, residing at Hartford, in the county of Hartford and State of Connecticut, have invented certain new and useful Improvements in Toilet-Paper, of which the following is a full, clear, and exact specification.

This invention relates to an improved arrangement of toilet-paper sheets by which are secured the advantages of economy of material, ease of detaching from the package, and better adaptation for its purpose when detached. The usual commercial form of toilet-paper is a sheet made extremely thin for greater pliability, which when put up in the usual package form is objectionable because of the difficulty of separating the desired number of these extremely thin sheets by means 20 of their close-lying edges. Because of the thinness of the paper with its great liability to imperfections it is necessary to use at least two sheets at a time, and in attempting to detach the sheets the user almost invariably takes 25 more at a time than are required, with the result that the surplus sheets are wasted. These and other obvious disadvantages are overcome in my present invention by superimposing and fastening together single sheets 30 of paper in such a way as to form a composite sheet having a central zone of two or more plies and thinner marginal zones. A package formed of these composite sheets presents distinct advantages in the matter of detaching the sheets, as is hereinafter fully set forth.

Figures 1 and 2 of the drawings are a side and an end view, respectively, of my preferred form of the present invention. Figs. 3, 5, and 7 are side views, and Figs. 4, 6, and 8 are end views, respectively, of three modified forms of my invention. Fig. 9 is an isometric view of the improved package formed by these sheets. Fig. 10 is an isometric view of the lower portion of the package of Fig. 9, illustrating how the members of the composite sheet separate when seized for the purpose of detaching it from the package. Fig. 11 is an end view of another modified arrangement of the sheets. Fig. 12 is an end

view, and Fig. 13 is a side view, of a two-ply composite sheet having both of its single marginal edges folded over upon lines corresponding in position to the line 21 22 shown upon the right-hand margin of Fig. 1. Figs. 5 5 and 15 are an end and a side view, respectively, of a two-ply composite sheet similar to that of Figs. 3 and 4, with both its single-ply margins folded upon lines substantially at the longitudinal centers of those margins. 6 Fig. 16 is an isometric view of a package formed of sheets like that of Figs. 12 and 13.

In the preferred form of my invention shown in Figs. 1 and 2 I employ two sheets of paper 1 and 2 of the length of sheet I desire to make, but narrower than the desired width. Paste or gum is applied to either of the sheets at the small spots *g*, preferably at some distance from the edges or from each other, for the purpose hereinafter explained. 7c The sheets are then placed one upon the other in such a way as to form a two-ply central zone 3, united by the spots of paste *g*. The width of this central zone I prefer to make of a width equal to about one-half the 75 entire width of the composite sheet.

In the modified form shown in Figs. 3 and 4 the composite sheet is formed of the sheet 4 of the full size desired and of the sheet 5 of the size of the desired two-ply zone united 80 by the spots of paste *g*. A further modification of the two-ply sheet is shown in Figs. 5 and 6, and it is similar to that of Fig. 4, except in its two-ply zone 6, which is here shown to be shorter than the length of the lower 85 sheet 4.

Figs. 7 and 8 show another modification of my invention, composed of three sheets 7, 8, and 9. The sheet 7 is of the full size desired, upon which is placed the narrower sheet 8, 90 and upon this the smallest sheet 9 is shown. These three sheets are united by the spots of paste *g*, forming a three-ply composite sheet. A modification of the three-ply sheet is shown in edge view in Fig. 11, wherein three sheets 95 10, 11, and 12 of substantially equal width are so superimposed and united as to form a composite sheet having a three-ply central zone, a two-ply zone on either side thereof, and single-ply marginal zones.

It is obvious that the proportions of the individual sheets which form the composite sheets herein shown may be varied in size and shape to a great degree while retaining 5 the principle feature of a central zone formed of a plurality of plies.

Among the advantages to be found in this improved form of toilet-paper may be stated the following: Greater safety, due to the use 10 of a plurality of sheets secured together sufficiently to retain them in their relative position and to the circumstance that any holes or other imperfections which may occur in any one of the single sheets will be covered 15 by its adjacent sheet, as shown in Figs. 3 and 4 at 13 and 14, respectively; economy of material, inasmuch as it is not necessary that the different members of the composite sheet shall be coextensive, but that the added thickness 20 may be disposed where needed and omitted elsewhere. Further, economy of material is gained, in that the thinner grades of toilet-tissues may be utilized in this invention. Greater pliability is also due to this latter circumstance 25 in connection with the way in which the members of the composite sheets are fastened together in spots, thus permitting them to bend and move freely one upon the other between those spots as compared with a single sheet of 30 the same thickness and strength as the composite sheet or as compared with a composite sheet the members of which are pasted together throughout their entire area. A toilet-package formed of these composite sheets is 35 possessed of great utility in the ease and certainty with which those sheets may be detached singly from the package, as illustrated in Fig. 10. By pressing the forefinger against the package upon the member 2, as represented 40 at the point 15, that portion is depressed, causing a corresponding distension at the edge of the member 1, as shown at 16, due to the circumstance of those members being connected by the isolated spots of paste *q* at some 45 distance from their edges. The distended portion 16 is seized between the thumb and forefinger and the composite sheet detached from the package by a slight pull.

I am aware that sheets of paper have been 50 put together with their ends slightly overlapping and with their alternate ends so secured together with weak gum as to form a continuous zigzag web and so that the operation of detaching a sheet shall cause the end 55 of the succeeding sheet to be drawn away from the package, thus enabling it in turn to be seized more readily; but none of those systems, to my knowledge, make any provision whereby two or more sheets fastened together 60 ready for use may be detached from the package at a single movement of the hand. I am also aware that various means are employed for the manipulation of toilet-paper in the roll, whereby the loose end of the web is presented, so as to be readily grasped; and it is 65 obvious that the various forms of my composite paper may also be used in roll form by be-

ing made into long webs either with or without transverse cuts or perforations to indicate where they should be severed.

Various methods and devices by means of which this improved paper may be produced are to form the subject-matter of subsequent applications.

The forms of the individual sheets making 75 up the composite sheet are shown of rectangular form in the drawings. In Fig. 5 I have shown in dotted lines the lower sheet 4 with angular edges 17 and the upper dotted sheet 18 of diamond shape. These forms 80 may be still further varied without departing from the spirit of the invention.

In Fig. 1 the sheets 1 and 2 are shown slightly mismatched longitudinally at 19. These two sheets may be mismatched to a 85 greater extent without impairing the value of the product, enabling the composite sheet to be seized at the end also as well as the sides in order to detach it. The fastener 20 of the package would in this case pass through single sheets, enabling the composite sheet to be 90 pulled off more easily.

The several sheets forming the composite sheet may be secured together with paste, 95 gum, or by any other means—as, for example, by embossing them together in spots, under pressure, without the use of any adhesive substance.

The composite sheet shown in Fig. 1 may be reduced in compass by having one or both 100 of its single-ply edges folded over upon itself longitudinally at the line 21 22, but not pasted. This will have the effect of reducing the width 105 of the package, making it uniform in thickness and density for greater convenience in manufacturing, cutting, and wrapping, and confers upon it the additional advantage of enabling the turned-over edge to be more readily seized in detaching the composite sheet from the package.

I claim as my invention—

1. As a new article of manufacture, a compound toilet paper sheet formed of single sheets of thin toilet paper laid face to face and secured together at isolated spots to form 115 a composite sheet, the edge of one sheet projecting beyond the edge of the other sheet, as specified.

2. A composite sheet of toilet paper, formed 120 of a plurality of single sheets of thin toilet paper having portions of their surfaces superimposed and secured together by adhesive material at isolated portions only of their meeting surfaces, forming a thickened yet pliable central zone for the purpose specified.

3. A composite sheet of toilet paper, formed 125 of a plurality of single sheets of thin toilet paper having portions of their surface superimposed and secured together at isolated portions only of their meeting surfaces to form a thickened yet pliable zone for adaptation 130 to its ultimate use, and having one or both of its single-ply edges folded over upon itself for the temporary purposes specified.

4. As a new article of manufacture, a toilet paper package made by securing together a number of composite sheets, each of which is composed of a plurality of single sheets of thin toilet paper having portions of their surfaces superimposed and secured together by adhesive material at portions only of their

meeting surfaces, leaving other portions of those meeting surfaces separable for the purpose specified.
